UNITED STATES PATENT OFFICE

HOWARD O. NELSON AND ROY J. LA BELLE, OF MINNEAPOLIS, MINNESOTA

DESIGN FOR A TILE BLOCK

Application filed May 11, 1929. Serial No. 31,183. Term of patent 7 years.

To all whom it may concern:

Be it known that we, HOWARD O. NELSON and ROY J. LA BELLE, both citizens of the United States, and both residing at Minneapolis, in the county of Hennepin and State of Minnesota, have invented a new, original, and ornamental Design for Tile Block, of which the following is a specification, reference being had to the accompanying drawing, forming a part thereof, wherein—

Fig. 1 is a perspective view of the tile block showing my new design; and

Fig. 2 is a view in rear side elevation of the block.

What is claimed is:—

The ornamental design for a tile block substantially as shown.

HOWARD O. NELSON.
ROY J. LA BELLE.
